RESPIRATOR

George E. Martindale, Lakewood, and Otto W. Scharping, Cleveland, Ohio, assignors to The Martindale Electric Company, Lakewood, Ohio, a corporation of Ohio

Application September 8, 1941, Serial No. 409,954

5 Claims. (Cl. 128—146)

Our invention relates to respirators, more particularly to that type of respirator embodying a filter for the purpose of filtering air inhaled and exhaled by a wearer, and the principal object of our invention is to provide new and improved respirators.

In the drawing accompanying this specification, and forming part of this application, we have shown, for purposes of illustration, an embodiment which our invention may assume, and in this drawing:

Figure 1 illustrates the embodiment as it is applied to the face of a wearer,

Figure 2 is an enlarged perspective view of the embodiment,

Figure 3 is a side elevational view of the embodiment; and

Figure 4 is a longitudinal central sectional view, illustrating the embodiment in position on the face of a wearer.

Referring to the drawing, the embodiment herein shown comprises a support 10, between which and the face of the wearer is adapted to be interposed filter means 11. The support 10 comprises a chin portion 12, a mouth portion 13, and a nose portion 14. The support is made of material capable of being formed to a definite shape, but being bendable and formable by the wearer, by sufficient manual manipulation, to any shape desired.

It is preferable to form the support 10 as a wire frame, as herein shown, the wire having such qualities which permit the frame to be bent and formed. Also, it is preferable to form the frame of a single length of wire, and as herein shown, the wire is bent approximately at its mid-point, forming a loop 15 having its legs 16 curved upwardly and approaching each other. The legs 16 are preferably joined in any suitable manner, as by brazing shown at 17. The loop 15 and legs 16 of the wire frame in this embodiment form the chin portion 12 of the support 10.

From their connection, the legs 16 diverge with respect to each other, forming a generally U-shaped portion 13 having legs 19. As best seen in Figure 3, the U-shaped portion 13 and its legs 19 are curved rearwardly (with respect to the face of the wearer, and out of the plane of the legs 16) to better fit the face of the wearer. The end of each leg 19 is bent forwardly (with respect to the rearward bend of the legs 19 and U-shaped portion 13), and these ends form nose pieces 20 adapted to be positioned on opposite sides of the wearer's nose. The extremity of

each nose piece 20 is formed with a small loop 21 to prevent injury to the face of the wearer.

In this embodiment, the U-shaped portion 13 and its legs 19 form the mouth portion 13, and the nose pieces 20 form the nose portion 14. As seen in Figure 1, the mouth portion 13 subtends the mouth area of the wearer, and provides an opening through which mouth breathing is permitted.

Each leg 19 of the U-shaped portion 13 is formed with an offset part 22 for receiving a loop provided on one end of respective holding straps 23, 24. Each strap is preferably formed of suitable elastic material. The strap 23 is provided with a hook 25 and an adjustment clasp 26, while the strap 24 is provided with an eye 27, adapted to receive the hook 25. When the clasp 26 has been adjusted to provide for correct length of the strap 23, the straps 23, 24 are connected at the back of the wearer's head, by engaging the hook 25 with the eye 27. As seen in Figure 1, the straps 23, 24 pass over the ears of the wearer, and resiliently pull on the support 10, so that the support bears firmly against the filter means 11, which in turn bears firmly against the face of the wearer.

The support 10 provides spaced points between which extends means for pressing the filter means against the nostrils of the wearer. Preferably, such means should be resilient, and as here shown, such means comprises a weak coil spring 28. Each leg 19 of the U-shaped portion 13 is bent to provide a notch 29, and the ends of the spring 28 are looped over the adjacent part 30 of respective notches 29, and in this manner the spring is anchored in position against movement along the legs 19.

The filter means 11 here shown comprises a filter pad 30, preferably of such size to extend over the mouth and nose area of the wearer's face, and as best seen in Figures 1 and 2, the filter pad 30 is of a larger area than the mouth and nose portions 13, 14, so that it overlaps these portions. The filter pad may be formed of a layer of cotton 31 sandwiched in between outer layers of gauze 32. The filter means 11 is secured to the support 10 in any suitable manner. In the embodiment shown, it has been found sufficient to use ordinary paper clips 33, which are positioned to clip the adjacent portion of the filter pad to a respective one of the straps 23, 24.

In use, after the length of the strap 23 has been adjusted consistent with comfort to the wearer, the respirator is positioned on the face so that the wearer's nose and the adjacent portion of the

filter pad extend through the space between the nose pieces 20, and the straps 23, 24 are connected at the back of the wearer's head by engaging the hook 25 with the eye 27.

The straps 23, 24, being somewhat resilient, exert a pull toward the upward with respect to the face of the wearer, the pull toward the face causing the legs 16, U-shaped portion 18, and legs 19 to press the filter pad against the face of the wearer so as to seal the mouth area and prevent any air from being inhaled or exhaled through the mouth except through the filter pad 30. The upward pull of the straps 23, 24 causes the spring 28 to press an adjacent portion of the filter pad to position overlying the nostrils of the wearer and thus prevent any air from being inhaled or exhaled through the nostrils except through the filter pad 30. The upward pull causes the spring 28 to flex out of its normal longitudinal position, so that the adjacent portion of the filter pad 30 is pressed to overlie not only the nostrils, but also to overlie the sides of the nose.

The nose pieces 20 bear against the sides of the looped upper portion of the filter pad (formed by the nose extending through the nose pieces) and press the adjacent portions of the filter pad against respective sides of the nose, thus preventing any tendency of such portions from falling away from the sides of the nose, and therefore obviating any possibility of an air leakage past the filter pad 30 and to the nostrils. As best seen in Figure 4, the spring 28 is of relatively small diameter and engages the wearer's head adjacent the meeting point of the nose and upper lip portion, and therefore provides no obstruction to breathing through the nostrils.

The chin portion 12 engages under the chin of the wearer, and assists in holding the respirator in position, as well as relieving the nose of any excessive strain which might be produced by the straps 23, 24, or the spring 28, or a combination of the two. Should the strain on the nose be excessive and uncomfortable, the wearer need only bend the chin portion 12 so that the distance between the loop 12 and the spring 28 is shortened. From a shipping standpoint, to economize on packing, it may be desirable to ship the respirator flat, that is, with the chin portion, mouth portion, and nose portions lying in a common plane. Under such circumstances, the wearer, upon initial use, may bend and form the support 10 to his individual requirements.

It will be apparent to those skilled in the art that we have accomplished at least the principal object of our invention, and it also will be apparent to those skilled in the art that the embodiment herein described may be variously changed and modified, without departing from the spirit of the invention, and that the invention is capable of uses and has advantages not herein specifically described; hence it will be appreciated that the herein disclosed embodiment is illustrative only, and that our invention is not limited thereto.

We claim:

1. A respirator, comprising: a frame, formed of formable wire; a filter pad, adapted to be interposed between said frame and the face of the wearer, and of such length and width that in position it has portions overlying the mouth and nose of the wearer; said frame having a generally U-shaped portion subtending the mouth area of the wearer and adapted to press the adjacent portion of said filter pad against the mouth area

of the wearer, and said U-shaped portion having spaced-apart legs, the end portions of which are constructed and arranged to hold the adjacent portion of said filter pad against the sides 5 of the wearer's nose; and a coil spring extending between said legs, constructed and arranged to press the adjacent part of said filter pad against the nostrils of the wearer; holding means, holding said frame in position on the 10 wearer's face; and said frame having a chin piece adapted to engage under the wearer's chin and relieve the nose of the wearer of uncomfortable pressure.

2. Means for holding flexible air filter means 15 against the nostrils of a wearer, comprising: support means, having spaced parts, and constructed and arranged to be positioned overlying the face of the wearer so that said spaced parts are positioned on the two sides of the nose of 20 the wearer; tie means, having its ends attached to said spaced parts, flexible downwardly relative to said ends, constructed and arranged to be positioned underlying the nose of the wearer when said support means is in position; and means for holding said support means and said tie means in position, constructed and arranged to exert an upward pull on the ends of said tie means to cause said tie means to flex about the base of the nose of the wearer and draw such 30 flexible air filter means against the nostrils of the wearer.

3. Means for holding flexible air filter means against the nostrils of a wearer, comprising: support means, having spaced parts, and constructed and arranged to be positioned overlying the face of the wearer so that said spaced parts are positioned on the two sides of the nose of 35 the wearer; resiliently extensible tie means, having its ends attached to said spaced parts, flexible downwardly relative to said ends, constructed and arranged to be positioned underlying the nose of the wearer when said support means is in position; and means for holding said support means and said tie means in position, constructed and arranged to exert an upward pull on the ends of said tie means to cause said tie means to flex about the base of the nose of the wearer and draw such 40 flexible air filter means against the nostrils of the wearer.

4. Means for holding flexible air filter means against the nostrils of a wearer, comprising: support means, having spaced parts, and constructed and arranged to be positioned overlying the face of the wearer so that said spaced parts 55 are positioned on the two sides of the nose of the wearer; tie means, having its ends attached to said spaced parts, flexible downwardly relative to said ends, constructed and arranged to be positioned underlying the nose of the wearer when said support means is in position; and means for holding said support means and said tie means in position, constructed and arranged to exert an upward pull on the ends of said tie means to cause said tie means to flex about the 60 base of the nose of the wearer and draw such flexible air filter means against the nostrils of the wearer; said support means comprising also chin-piece means adapted to engage beneath the chin of the wearer to limit upward movement of 65 said support means to prevent excess pressure by said tie means against the end of the nose of the wearer.

5. Means for holding flexible air filter means against the nostrils of a wearer, comprising: support means, having spaced parts, and con-

structed and arranged to be positioned overlying the face of the wearer so that said spaced parts are positioned on the two sides of the nose of the wearer; resiliently extensible tie means, having its ends attached to said spaced parts, flexible downwardly relative to said ends, constructed and arranged to be positioned underlying the nose of the wearer when said support means is in position; and means for holding said support means and said tie means in position, constructed and arranged to exert an upward pull on the ends

5 of said tie means to cause said tie means to flex about the base of the nose of the wearer and draw such flexible air filter means against the nostrils of the wearer; said support means comprising also chin-piece means adapted to engage beneath the chin of the wearer to limit upward movement of said support means to prevent excess pressure by said tie means against the end of the nose of the wearer.
